UNITED STATES PATENT OFFICE

NELSON VOYLE JOHNSON, OF FULLERTON, CALIFORNIA

DRIER APPARATUS

Application filed May 29, 1929. Serial No. 367,052.

This invention relates to a drier apparatus and has relation more particularly to an apparatus of this kind especially designed and adapted for use in a beauty parlor or the like 5 for the drying of hair.

It is an object of the invention to provide a device of this kind wherein is adapted to be created two blasts of air of different temperatures together with means for regulating the discharge of one of such blasts independently of the other.

The invention consists in the details of construction and in the combination and arrangement of the several parts of my improved drier apparatus whereby certain important advantages are attained and the device rendered simpler, less expensive and otherwise more convenient and advantageous for use, as will be hereinafter more 20 fully set forth.

The novel features of my invention will hereinafter be definitely claimed.

In order that my invention may be the better understood, I will now proceed to describe the same with reference to the accompanying drawing, wherein:

Figure 1 is a view partly in top plan and partly in section illustrating a drier apparatus constructed in accordance with an embodiment of my invention;

Figure 2 is a fragmentary view partly in section and partly in elevation, the line of section being taken substantially on the line 2-2 of Figure 1;

Figure 3 is a sectional view taken substantially on the line 3-3 of Figure 1;

Figure 4 is a view in side elevation of the fan mechanism for creating the hot blast;

Figure 5 is a sectional view taken substantially on the line 5-5 of Figure 3 with the carry-off pipe omitted;

Figure 6 is a sectional view taken substantially on the line 6-6 of Figure 3.

As disclosed in the accompanying drawing, 1 denotes an elongated casing of desired dimensions and configuration adapted to be supported in any desired manner in working position with the walls of said casing 1 being preferably made of metal and each of

said walls having disposed thereover a lamination 2 of asbestos.

In the present embodiment of my invention, the casing 1 has in communication therewith through the bottom wall thereof three outlet pipes 3 spaced lengthwise of the casing 1 and with a fourth outlet pipe 4 in communication with the casing 1 through an end wall thereof. Each of these outlet pipes 3 and 4 is adapted to have coupled thereto a carry-off pipe 5 preferably of flexible metal. This flexible pipe 5 is adapted to discharge as desired.

Extending lengthwise through the casing 1 is a pipe or conduit 6 preferably of galvanized metal having outlet pipes 7 extending within the outlet pipe 3, said pipes 7 terminating inwardly of the pipes 3 and of a less diameter. This pipe or conduit 6 also has an outlet pipe 8 extending within the outlet pipe 4 but terminating inwardly thereof and of less diameter. Each of the outlet pipes 7 and 8 has mounted therein a regulating valve or damper 9 having an operating stem 10 extending exteriorly of the adjacent or associated outlet pipe 3 or 4. By proper manipulation of each of the valves 9 the discharge of heated air through the coating discharge pipe 7 or 8 may be readily regulated or controlled as desired.

In communication with the end portion of the casing 1 remote from the outlet pipe 4 is an inlet pipe 11 in suitable communication with the discharge nozzle 12 of a fan casing 14. The pipe 6 is extended, as at 15, through the same end wall of the casing 1 and is in proper communication with the nozzle 16 of a second fan casing 17. The fan casings 14 and 17 are arranged side by side and have disposed therethrough a common shaft 18 herein disclosed as driven by an electric motor 19. The shaft 18 within each of the casings 14 and 17 has radiating therefrom fan blades 20 so that when the shaft 18 is in rotation the desired blasts of air will be directed into the casing 1 and also through the pipe 6.

The casing 14 has a side wall or face in communication with the atmosphere while a

side wall or face of the casing 17 is in communication with an intake box 21.

This box 21, through the medium of a suitable conduit 22, is in communication through the top with a hood H. This hood H is of such configuration and dimensions as to be readily applied over a gas heater whereby effective means are provided to heat the air drawn into the casing 17 and discharged through the pipe 6.

With an apparatus constructed in accordance with an embodiment of my invention, it is believed to be apparent that it can be employed with advantage in beauty parlors or the like especially in view of the fact that the cold and heated air can be mixed under regulation as may be desired.

From the foregoing description it is thought to be obvious that a drier apparatus constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as herein-after claimed.

I claim:—

1. An apparatus of the class described comprising a casing, means for forcing a blast of air within the casing, a pipe extending through the casing, means for forcing a blast of free heated air through the pipe, an outlet pipe in communication with the casing,

40 an outlet pipe in communication with the pipe and extending within the outlet pipe of the casing, and means for controlling the flow through one of said outlet pipes.

2. An apparatus of the class described comprising a casing, means for forcing a blast of air within the casing, a pipe extending through the casing, means for forcing a blast of free heated air through the pipe, an outlet pipe in communication with the casing, 50 an outlet pipe in communication with the pipe and extending within the outlet pipe of the casing, and means for controlling the flow through the outlet pipe in communication with the pipe.

55 3. An apparatus of the class described comprising a casing, means for forcing a blast of air within the casing, a pipe extending through the casing, means for forcing a blast of free heated air through the pipe, an outlet pipe in communication with the casing,

60 an outlet pipe in communication with the pipe and extending within the outlet pipe of the casing, a controlling valve within the outlet pipe in communication with the pipe and 65 an operating stem for said valve extending

exteriorly of the outlet pipe in communication with the casing.

In testimony whereof I hereunto affix my signature.
